UNITED STATES PATENT OFFICE

2,072,905

AUTOMATIC TRAIN PIPE CONNECTER

Joseph Robinson, New York, N. Y., assignor of
one-half to Roy M. Wolvin, Montreal, Quebec,
Canada

Application August 29, 1934, Serial No. 741,988
Renewed June 19, 1936

7 Claims. (Cl. 285—58)

In recent years the size of the pipes carrying steam for heating purposes on railway passenger cars has been increased, but by reason of the numerous bends and right angle turns in these 5 pipes it is still difficult to force steam from the locomotive back to the rear car of a long passenger train in adequate amounts to properly heat the last car. In consequence high pressures must now be employed at the front end of the 10 train. These high pressures, with their accompanying high temperatures, and the movements and strains the hand manipulation of hose impose, soon destroy the conventional rubber steam hose. To meet this condition flexible metallic 15 hose, such as illustrated in Figure 1 of my United States Patent 1,896,918, has been developed. Unavoidably these metal hose are heavy and stiff, and when coupled and uncoupled by hand the wear on their several joints is considerable.

20 For some years devices for coupling and uncoupling the steam and other hose between railway cars automatically, have been under consideration by the railroads. Many tests have been conducted, and in these it has been established that the heavy weight and stiffness of 25 the metal hose impose a serious burden to the operation of the connector. My invention provides means for distributing this weight on and for attaching the metal hose to the connector in 30 such a way as to completely minimize this burden and greatly reduce the movement of and hence the wear on the joints of metal hose. The "easing" feature of my improvement by which these advantages are obtained encourages and 35 permits the use of a special type of reinforced high pressure steam rubber hose in place of the heavy, cumbersome and expensive metallic hose. The change not only effects a large saving, but eliminates from a train many of the right angle 40 turns and projections in the steam line which restrict the flow of steam and require the high pressures mentioned.

In the drawing, Figure 1 is a side elevation of my improvement taken on the steam hose side of the connector;

45 Figure 2 is a side elevation of my improvement as seen from the side opposite to that shown in Figure 1, and

Figure 3 is a front view detail of the supporting lug 11 showing the conduit 10 in place thereon.

The usual coupling head A is carried by a hollow yoke B, which spans the lower portion of a bracket C that is suitably attached to the car coupler as by a lug D and bolts 3. At its rear 55 end the yoke is provided with a flange 4 which receives and supports the forward end of a suitable buffer spring E of substantial inside diameter. A tie rod 5 extends forwardly through this spring and through a large opening in the flange 4 and 60 pivotally embraces the bracket between the verti-

cally narrow straps or walls 6 of the yoke. These walls terminate in vertically wide flared centering portions 7 which normally engage the laterally extending lugs 8 of the bracket to vertically position the yoke thereon. An adjustable abutment or nut F anchors the several parts together under the desired spring pressure. The arrangement permits universal movement of the coupling head A, and its novel feature is the wide range of vertical movement permitted to the yoke 10 B, relative to the bracket C, when the connector is coupled moving the narrow walls 6 of the yoke rearwardly until they lie approximately between the lugs 8, Figure 2. In this position the yoke 15 and coupling head float or rock easily on the forward end of the spring E, effectively eliminating the jerking jarring strains that, with a more rigid joint, occur in shifting the heavy stiff metal hose G when the cars lurch vertically or in rounding a curve. This sensitivity to movement 20 absorbs a large range of the changes in position which the bracket C undergoes in service without causing any appreciable movement of the hose G. The result is the minimum of burden on the coupled connector heads, and the minimum of wear on the ball and socket or other joints 25 9 of the hose.

Further protection for the hose and the coupling head A is secured by my improved means for attaching the steam hose G to the connector and 30 distributing its weight thereon. This includes a relatively long conduit 10, which suitably supports or carries at its forward end a gasket H of any desired type. The rear portion of the conduit is dropped away from the underside of the yoke B 35 to provide clearance for the lower cross members or lugs 8 of the bracket. The forward end of the conduit is suitably and removably supported on or in the connector head, and the rear end is removably supported on a seat or lug 11, Figure 3, 40 which is integral with the flange 4. Upwardly extending projections 12 on the conduit straddle the lug 11 to properly position the conduit on the lug and prevent movement thereon in service. The conduit is anchored to the lug, and hence to 45 the yoke B, by means of a plunger or thrust pin 14 moving longitudinally, and slightly upwardly, through a pair of spaced brackets or bearings 15 attached to the flange 4. The pin 14 is locked against rotation in its bearings, and threadingly 50 receives a wing nut 16 by which the pin is shifted into and out of engagement with the seat 11 on the conduit 10. The length of the conduit is such as will bring the connection between it and the hose G directly under, and in the plane of, the 55 pivotal point of the yoke B and tie rod 5, when the connector is coupled, see line 18 Figure 2. This novel feature provides the important advantage of taking off of the coupling head A the heavy strains it would otherwise be placed under 60

when the car couplers of running cars shift in their carrier irons in a direction away from the steam hose G. During such movement the yoke B is drawn against the side of the bracket D at its 5 lower end, and since the connection of the hose G to the coupled head A is approximately directly under the bracket, and not far ahead of it, as heretofore, all of the considerable pull required to move the hose, which is burdensomely very 10 stiff under high steam pressure, is completely removed from the connector head and the joints formed by it.

With the movement of the steam hose reduced to the minimum by the protecting "easing" feature which the foregoing constructions and arrangement of parts produce, it will be seen why a special type of smooth bore steam rubber hose, reinforced and constructed to withstand the steam pressures and temperatures, may if desired be used with my improvement in place of the cumbersome and costly metallic hose, the right angles and obstructions in which impose so much resistance to the flow of steam through the train line.

25 What I claim is:

1. An automatic train pipe connector comprising in combination, a coupling head, a bracket on which said head is pivotally supported, a train pipe hose for directing a fluid to said head, and 30 means for connecting said hose with said head with the minimum of movement of said hose and with the minimum of service strains on both the hose and the head when said head is coupled, said means including a conduit extending rearwardly 35 from said head with its rear end disposed, when said head is coupled, in approximately a vertical plane passing through the pivotal point of said head on said bracket, said rear end of the conduit being connected with the train pipe hose.
- 40 2. An automatic train pipe connector comprising in combination, a coupling head, a bracket on which said head is pivotally supported, a member connecting the head and bracket, a train pipe hose for directing a fluid to said head, and means 45 for connecting said hose with said head with the minimum of movement of said hose and with the minimum of service strains on both the hose and the head when said head is coupled, said means including a conduit extending rearwardly from 50 said head with its rear end disposed, when said head is coupled, below and in approximately the plane of the pivotal point of said head on said bracket, and means for securing the rear end of said conduit to said member.
- 55 3. An automatic train pipe connector comprising in combination, a coupling head, a bracket on which said head is pivotally supported, a member connecting the head and bracket, a train pipe hose for directing a fluid to said head, and 60 means for supporting said head with the minimum of movement on said hose and with the minimum of service strains on both the hose and the head when said head is coupled, said means including a conduit extending rearwardly from 65 said head with its rear end resting, when said head is coupled, below and in approximately the plane of the pivotal point of said head on said bracket, and means for securing the rear end of said conduit to said member, said securing means 70 including a shiftable thrust pin for removably clamping said conduit in place.
4. An automatic train pipe connector comprising in combination, a coupling head, a bracket

on which said head is pivotally supported, a train pipe hose for directing a fluid to said head, and means for supporting said head with the minimum of movement on said hose and with the minimum of service strains on both the hose and the head when said head is coupled, said means including a member extending past said bracket and carrying said coupling head at its forward end, a coiled spring supporting the rear end of said member and yieldingly permitting a free 10 range of sensitive vertical movement of the member relative to said bracket, a conduit removably mounted in said head and on said member, and thrust means adjacent the front end of said spring for anchoring said conduit in place and 15 for tying said hose to said member.

5. An automatic train pipe connector comprising in combination, a coupling head, a bracket on which said head is pivotally supported, a train pipe hose for directing a fluid to said head, and 20 means for supporting said head with the minimum of movement on said hose and with the minimum of service strains on both the hose and the head when said head is coupled, said means including a member spanning the lower end of 25 said bracket and carrying said coupling head at its forward end, a coiled spring supporting the rear end of said member and flexing to yieldingly permit a free range of sensitive vertical movement of the member relative to said bracket, a 30 tie rod embracing the lower end of said bracket for anchoring said spring to the bracket and to said member, a conduit removably mounted in said head and on said member, and thrust means 35 for anchoring said conduit in place and for tying said hose to said member, said thrust means including a pin, a bearing in which the pin moves, and manually operated power means for shifting the pin in said bearing into and out of engagement with said conduit.

6. An automatic train pipe connector comprising in combination, a coupling head, a bracket on which said head is pivotally supported, a yoke connecting said head and bracket and spanning the latter, a conduit removably connected to said 45 head and lying below said yoke, seats on said bracket for said yoke, said seats including a pair of transversely extending lugs one of which lies above said yoke and the other of which lies between the yoke and said conduit, the rear portion of the conduit being dropped to clear the latter, and a threaded thrust pin carried by said yoke for rigidly but removably locking said conduit in place.

7. An automatic train pipe connector comprising in combination, a coupling head, a bracket on which said head is pivotally supported, a train pipe hose for directing a fluid to said head, and means for connecting said hose with said head with the minimum of movement of said hose and 60 with the minimum of service strains on both the hose and the head when said head is coupled, said means including a yoke which spans the lower portion of said bracket and cooperates therewith to pull said hose laterally in service, a 65 conduit extending rearwardly from said head with its rear end disposed, when said head is coupled, in approximately the plane of the vertical pivotal movement of said head on said bracket, and thrust means for anchoring said 70 conduit in place.

JOSEPH ROBINSON,
